UNITED STATES PATENT OFFICE.

JOHN K. DARBY AND DANIEL LUCAS, OF PUYALLUP, WASHINGTON.

HEN'S NEST.

Application filed March 17, 1927. Serial No. 176,094.

This invention aims to provide a novel means whereby after an egg has been laid, the egg will be permitted to pass into a separate compartment, thereby preventing a breaking of the egg, and permitting a laid egg to be removed from one part of the nest whilst a hen still is laying an egg in another part of the nest.

It is within the province of the disclosure 10 to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the 20 invention herein disclosed, may be made within the scope of what is claimed, without departing from the spirit of the invention.

In the drawings:—

Figure 1 is a top plan wherein parts are 25 broken away;

Figure 2 is a front elevation wherein parts are broken back into section;

Figure 3 is a horizontal section;

Figure 4 is a transverse section;

Figure 5 is a transverse section showing 30 a modification; and

Figure 6 is a section taken about on the line 6—6 of Figure 5.

In carrying out the invention there is 35 provided a casing including a bottom 1, a front 2, a back 3, a top 6, and, if desired, supporting cleats 5 on the bottom 1. The front 2 does not extend the full height of 40 the casing and so there is formed at the front of the casing, an opening 7 by which the hen can enter and leave the nest. The casing is provided with any desired number 45 of transverse partitions 8 extended between the bottom 1 and the top 6, and between the front 2 and the back 3. The rear edges of the partitions 8 are inclined as at 9. A lid 10 rests on the inclined edges 9 of the partitions 8 and upon the upper edge 50 of the back 3, the lid 10 being hinged at 11 to the rear end of the top 6.

The device may be made with any desired number of compartments, but since there is no novelty in mere duplication, the 55 description will proceed in the singular number.

In the partitions 8, vertical guide grooves 12 are formed. In the guide grooves 12 a gate 14 slides. In its lowermost position, the gate 14 rests on a foraminous bottom 15, made of wire netting or the like, the bottom 15 slanting rearwardly from the upper edge of the front to the back 3. At the rear end of each compartment there is a cushion which may be made as desired. If preferred, the cushion may consist of a piece of resilient wire netting which is looped at 17 behind the partitions 8, the loops 17 being bound against the back 3 by the rear edges of the partitions. 60 Between the partitions 8, the netting or other material is extended forwardly as at 18 so as to space the netting from the back 3 and form a cushion against which the eggs 65 in another part of the nest ultimately roll.

The device includes a treadle lever 19 for each compartment. The treadle lever is a composite structure and may be composed of a U-shaped member 20, the side arms of which are designated by the numeral 21. 70 The side arms 21 may be distorted slightly to form seats 22 received in eyes or other fulcrum members 23 on the partitions 8. A tread plate 24 rests on the side arms 21 and on the intermediate portion of the U-shaped member 20, as disclosed in Figure 2, and the intermediate portion of the U-shaped member 20 is secured at 25 to the tread plate. The inner ends of the arms 21 of the treadle lever extend beneath the lower 75 edge of the vertically slidable gate 14 and rest on the inclined foraminous bottom 15. The tread plate 24 is located outside of the casing 1 at the lower end of the opening 7.

In practical operation, the hen enters the 80 nest by way of the opening 7 lays the egg in the main compartment which is designated by the numeral 26. The egg comes into contact with the gate 14 and there remains until the hen leaves the nest. As 85 the hen leaves the nest, the hen steps on the tread plate 24, and the treadle lever 19 is tilted on its fulcrum 23, the gate 14 being raised in the guide grooves 12 and the eggs being permitted to roll backwardly and 90 downwardly along the foraminous bottom 15 into contact with the cushion 18 which will yield enough to prevent the eggs from being cracked or smashed. When the hen 95 steps off the foot plate 24, the gate 14 moves by gravity to a closed position, and the nest is ready to be used by another hen. The 100 105 110

egg may be removed at any time by lifting the lid 10 and this may be done without disturbing a hen which may happen to be in the compartment 26.

5 An egg when first laid is somewhat moist, but dries rapidly. If a moist egg is permitted to roll very far, it will collect dust, which spoils the appearance of the egg. In the device forming the subject matter of 10 this application, the egg rests against the gate 14 and remains there until the hen steps on the tread plate 24. During this interval, the egg has time to dry and as it rolls back against the cushion 18, the egg 15 does not collect dust from the bottom 15.

In Figures 5 and 6, parts hereinbefore described have been designated by numerals previously used, with the suffix "a". In this modification, the arms 21^a of the 20 treadle lever 19^a are provided at their ends with upstanding fingers 40 to which the gate 14^a is secured, as shown at 41.

This hen's nest may be manufactured from wood, or metal, or partly from wood 25 and partly from metal.

What is claimed is:—

1. In a device of the class described, a nest having main and auxiliary compartments, a gate movable in the nest and separating the compartments, and a treadle lever fulcrumed intermediate its ends in the nest, one end of the treadle lever cooperating with the gate to raise the gate when

the other end of the treadle lever is depressed, and an inclined bottom constituting means for carrying an egg rearwardly from the main compartment to the auxiliary compartment when the gate is raised. 35

2. In a device of the class described, a nest having a rearwardly inclined bottom, 40 a positive egg-stop in the form of a gate movable above the bottom and dividing the nest into main and auxiliary compartments, and means operated by a hen as the hen leaves the nest, for opening the gate and moving it out of egg-stopping position, thereby to permit an egg to roll from the main compartment to the auxiliary compartment. 45

3. In a device of the class described, a 50 casing having partitions, a gate movable between the partitions and dividing the casing into main and auxiliary compartments, a treadle lever cooperating with the gate to raise the gate and fulcrumed intermediate its ends on the partitions, and a rearwardly inclined bottom extended from the front to the back of the casing and constituting means for directing an egg from the main compartment into the auxiliary 55 compartment, when the gate is raised. 60

In testimony that we claim the foregoing as our own, we have hereto affixed our signatures.

JOHN K. DARBY.
DANIEL LUCAS.
